UNITED STATES PATENT OFFICE.

JOHN EDWARD JOHNSON, OF RONCEVERTE, WEST VIRGINIA.

HAT, COAT, OR BAGGAGE CHECK.

1,172,602.

Specification of Letters Patent.

Patented Feb. 22, 1916.

Application filed December 10, 1915. Serial No. 66,105.

To all whom it may concern:

Be it known that I, JOHN EDWARD JOHNSON, a citizen of the United States, residing at Ronceverte, in the county of Greenbrier, State of West Virginia, have invented a new and useful Hat, Coat, or Baggage Check; and I do hereby declare the following to be a full, clear, and exact description of the invention, such as will enable others skilled in the art to which it appertains to make and use the same.

This invention relates to a hat, coat, or baggage check, and an object of the invention is to provide a device of this character consisting of two parts, one part acting as a holder for the other part and provided with a clamp, to secure the part to the article or commodity that is being checked.

In practical fields the details of construction may necessitate alterations, falling within the scope of what is claimed.

The invention comprises further features and combination of parts, as hereinafter set forth, shown in the drawings and claimed.

In the drawings: Figure 1 is a view in perspective of the improved hat, coat, or baggage check. Fig. 2 is a view in front elevation of the check. Fig. 3 is a view in rear elevation. Fig. 4 is a sectional view on line 4—4 of Fig. 2. Fig. 5 is a sectional view on line 5—5 of Fig. 3. Fig. 6 is a view in front elevation of the part of the check that constitutes a holder for the other part.

Referring more especially to the drawings, 1 and 2 designate the two parts (which may be any suitable contour or configuration) of the check. However, in the present instance, the parts are circular or disk-shaped, and upon one face of each of the parts the number of the check is provided. As will be noted the numbers correspond in denomination. The part 2 (which is given to the person who is checking the article or the like) is supplied, upon the face having the number, with an annular groove 3, substantially semi-circular in cross section. The part 1 adjacent its lower edge is provided with a lug 4 bent laterally and upwardly to contact with the lower edge of the part 2 and overlie the front face of said part 2, to assist in preventing displacement of said parts. At one of the side edges of the part 1 a lug 5 is provided, which is bent laterally, so that the edge of the part 2 will contact therewith. This lug 5 also extends at right angles to the

plane of the upwardly extending part of the lug 4, to overlie the front face of the part 2. The extended part 6 of said lug 5 has upon its under face a protrusion 7, which is substantially semi-circular in cross section, so as to engage the annular groove 3, to further assist in preventing displacement of the part 2 of the check. Forming an integral part of the part 1 of the check diametrically opposite the lug 4 as shown at 8 is a clamping tongue 9, which curves rearwardly and extends downwardly, as shown in Figs. 3 and 5, to engage the lower portion of the rear face of the part 1. When checking either your hat or coat or both, or checking your baggage, the attendant of the hat box or the check room or baggage room removes the part 2 of the check from engagement with the part 1, the extension 6 of the lug 5 yielding as the part 2 is disengaged, and presents it to the owner of the wraps or baggage, after which the part 1 is attached to the baggage or the wraps, by virtue of the clamp 9. When the wraps or the like are called for, the part 2 is presented to the attendant, who locates the wraps having the correspondingly numbered part 1, and detaching the part 1 returns the wraps to the owner, and then slips the part 2 in engagement with the part 1, so that the two parts will be held together by the lugs 4 and 5 and the protrusion 7.

The invention having been set forth, what is claimed as new and useful is:

1. A wrap or baggage check, comprising two parts correspondingly numbered, one of said parts adjacent its edge having a pair of lugs, one extending at right angles to the other, said lugs having extensions extending toward the center of the part and at right angles to each other and adapted to overlie the other part, to retain the other part in position, and a spring clamp carried by one of the parts to attach the same to a wrap or baggage.

2. A wrap or baggage check, comprising two parts correspondingly numbered, one of said parts adjacent its edge having a pair of lugs, one extending at right angles to the other, said lugs having extensions extending toward the center of the part and at right angles to each other and adapted to overlie the other part, to retain the other part in position, the extension of one of the lugs having upon its under surface a protrusion,

one of said parts having an annular groove upon its outer face to be engaged by said protrusion to materially assist in holding the parts of the groove in engagement with said lug, and clamping means carried by one of the parts to attach the same to a wrap or baggage.

In testimony whereof I have signed my name to this specification in the presence of two subscribing witnesses.

JOHN EDWARD JOHNSON.
